TUNNEL LINING

Anthony Foukal, Cleveland, Ohio, assignor to
 Truscon Steel Company, Youngstown, Ohio, a
 corporation of Michigan

Application June 24, 1936, Serial No. 87,089

5 Claims. (Cl. 61—45)

The present invention relates to tunnels driven by the shield method, wherein a shield is driven through the ground by means of powerful hydraulic jacks, and a lining for the tunnel is constructed in the tail of the shield, and wherein the already constructed portion of the lining is used to take the thrust of the hydraulic jacks in pushing the shield ahead. Such linings are commonly constructed of successive courses of steel liner plates, the courses being assembled in the tail of the shield as the tunnel driving progresses. Where the liner plates making up the lining do not provide sufficient resistance to such thrust, which is exerted longitudinally upon the lining, means must be provided to withstand it in order to prevent the lining from being damaged.

It is common practice, where ground conditions make it necessary, to use suitable structural members between the successive courses of liner plates to support excessively heavy ground; but such structural members of course provide insufficient resistance to the thrust of the shield driving jacks.

The object of the invention is to provide a novel combination in a lining structure of both permanent and removable thrust-receiving members, which will provide not only sufficient strength to support the ground loading or circumferential load, but will also effectively resist the thrust exerted by the shield jacks.

Another object is to provide such a structure which will reduce to a minimum the amount of steel required to serve both purposes, and thus reduce to a very material degree the amount of steel that must be permanently left in place.

Still another object is to provide a lining structure including both permanent and temporary longitudinal thrust-resisting strut members, in which the latter are located directly in line with the former, so as to provide a perfect continuity of thrust-resisting members throughout that length of tunnel necessary to take the full thrust of the shield driving jacks.

Still another object is to provide removable thrust members that in addition to their thrust-receiving function, can be utilized to adjust the position of successive courses in order to take up any variation or slack in the assembly of such courses.

The use of removable thrust-members permits the jacks in the rear of the tunnel to be removed to a forward position immediately in the rear of the jacks as the lining progresses.

In the accompanying drawings:

Figure 1 is an end elevation partly in section of a lining structure.

Figure 2 is a sectional view on the line 2—2 of Figure 1.

Figure 3 is an enlarged view showing a side elevation of a section of the lining.

Figure 4 is a sectional view on the line 4—4 of Figure 3.

Figure 5 is a perspective view of a section of a lining.

Figure 6 is a detail elevation showing means for initially positioning the removable thrust members.

Figure 7 is a detail sectional view of a portion of one of the members, showing the preferred type of thread.

Describing the drawings more particularly, the liner plates are designated 8, and each comprises a backing or skin plate 9, the said skin plate being curved to conform to the circumference of the tunnel, and having along its straight edges end flanges 10, and along its curved edges side flanges 11.

The term "side" as applied to the plates refers to the long or curved edge, and the term "end" refers to the short or straight edge which is substantially parallel to the longitudinal axis of the tunnel.

The liner plates are of weight and size suited to their use as determined by the conditions under which the tunnel is built, and the flanges 10 are desirably formed integrally with the skin plate and continuously around its edges. The flanges 10 and 11 are pierced by suitable openings for the reception of bolts 12 or other fastenings for securing the plates together and to the supporting structure.

Between the adjacent courses of plates are located circumferential load-resisting members, here shown as I-beams, 13, although any suitable structural shape of proper weight and strain-resisting qualities may be used. The members 13 are pierced by openings through which pass the bolts 12 that secure together the plates composing adjacent courses.

The joints between the end flanges 10 of the plates of one course, as 14, are staggered with relation to those of the next course 15, and are in line with those of the next course but one 16, this arrangement being preferable for considerations of strength, etc., in the finished lining. Between the end flanges 10 of adjacent plates are interposed longitudinal thrust-receiving members which in in this embodiment are shown as T-beams 17 having flanges 18 interposed between the flanges 10, and heads 19 disposed inwardly of the inner margins of the flanges. The ends of these members are in abutting relation with the circumferential load-receiving members 13, so that the thrust exerted upon the end of the liner by the hydraulic jacks is transmitted longitudinally through the members 17 to the members 13.

The thrust-resisting members 17 of adjacent courses are in staggered relation and as the jacks drive the shield ahead, it will be appreciated that

the transmission of the thrust through the members 17 against portions of the beams 13 that lie between the members 17 of the next rearward course, would cause distortion of the beams and a consequent displacement of the elements of the lining and buckling or other disarrangement of the plates.

In order to overcome this without increasing the amount of steel permanently mounted in the 10 lining and left in place, the removable thrust-receiving jacks or struts 20 are installed in the courses in the manner shown in the drawings as the mining progresses. The form of these jacks 15 20 at present considered preferable is best illustrated in Figures 3 and 4, wherein each jack comprises a body portion in the form of an elongated member 21 having a central faced off angular portion 22 for engagement by a spanner or other wrench. The body portion 21 has extending 20 therethrough a bore 23, the end portions of which are oppositely threaded, as at 24 and 25.

Threaded into the ends of the bore 23 are threaded stems 26 and 27 having squared off 25 heads 28, the ends of which act as engaging surfaces. It will be understood that upon turning the body portion 21 with relation to the stems 26 and 27, the latter will be either extended or inwardly drawn.

The form of thread shown in Figure 6 is considered preferable due to the fact that it gives 30 great resistance to the strain exerted between the body and the stems.

The use of these devices will be clearly understood by reference to Figures 2 and 3. The jacks 35 20 are intended to be positioned between adjacent members 13, the surfaces of which they abut, and in end to end relation with the thrust-receiving members 17 of the courses on either side of the one in which the member 20 is placed. 40 It will be seen that with jacks as positioned, the thrust exerted by one of the members 17 of one course, as 16, will be transmitted through a member 13 to a jack positioned in the next course, as 15, and thereafter to the member 17 of the 45 next rearward course, as 14. The threaded engagement between the two stems and the body portion besides permitting the ready insertion and removal of the device, permits the ends of the stems to be forced into an absolutely rigid 50 abutting engagement with the members 13.

It will be noted by reference to Figure 4 that the members 17 extend inwardly of the liner beyond the flanges 10 and 11 of the liner plates. It will therefore be apparent that the removable 55 jacks 20 may be inserted between the members 13 inwardly of the flanges 11 and in direct abutting relation with the surfaces of the members 13.

In order to fix the position of the jacks with respect to the members 17 of adjacent courses, 60 lugs 29 may be welded in pairs to the surfaces of the members 13, and properly spaced to receive between them the squared ends of the stems. The inner edges of the flanges 11 also operate to properly position the ends of the stems.

65 By the combination of this lining structure with the removable struts, the advantages gained by the use of courses of relatively staggered plates may be retained and a great saving in the weight of steel used in the lining may be effected. 70 The various permanent elements are of suitable size and weight so that the combination of the two side flanges 10 of the liner plates with the structural members bolted between them will, with the removable adjustable strut members or 75 jacks, provide the necessary resistance to the

thrust of the hydraulic jacks which propel the shields.

From the foregoing, it is thought that the construction, operation and many advantages of the herein described invention will be apparent to 5 those skilled in the art, without further description, and it will be understood that various changes in the size, shape, proportion and minor details of construction may be resorted to without departing from the spirit or sacrificing any 10 of the advantages of the invention.

What I claim, is:

1. In a tunnel lining including a series of courses of liner plates, and circumferential load-bearing members between the courses, thrust- 15 resisting members permanently mounted between adjacent plates in each course, the ends of the said members being in abutting relation with the circumferential load-bearing members.

2. In a tunnel lining, including permanent 20 longitudinal thrust-resisting members in spaced end to end relation, and temporary thrust-resisting members removably mounted between and in end to end relation with the permanent thrust-resisting members, means constituting a portion 25 of the tunnel lining for engagement with the temporary members for supporting them in proper relation with the permanent members.

3. In a tunnel lining including a series of 30 courses of liner plates and circumferential load-bearing members arranged between adjacent courses, and permanent longitudinal thrust-resisting members mounted between the plates of the courses and in abutting relation with the circumferential load-bearing members, the thrust- 35 resisting members of one course being in staggered relation with those of the two adjacent courses, a plurality of lugs mounted upon the circumferential load-bearing members for engaging ends of the temporary thrust-resisting members, the lugs being properly spaced upon the load bearing members to position the temporary members in end-to-end relation with the permanent members of the adjacent courses.

4. In a tunnel lining including a series of 45 courses of liner plates the combination with a plurality of longitudinal thrust-resisting permanent members assembled with the liner plates, the thrust-resisting members of each course being in staggered relation with those of the adjacent courses, of a plurality of temporary thrust-resisting members removably mounted between and in end to end relation with the permanent thrust-resisting members of the two adjacent courses, and means carried by the tunnel lining 50 for engaging the ends of the removable thrust-resisting members.

5. In a tunnel lining including a series of 60 courses composed of liner plates having flanges along their sides and ends, and circumferential load-bearing members of greater height than the flanges positioned between adjacent courses, the combination of permanent longitudinal thrust-resisting members of greater height than the flanges, mounted in the courses between the 65 flanges of adjacent plates with their ends abutting the circumferential load-bearing members, and temporary thrust-resisting members removably mounted beyond the margins of the flanges of the plates and between the circumferential 70 load-bearing members, and between and in end to end relation with the permanent longitudinal thrust-resisting members of the adjacent courses.
